UNITED STATES PATENT OFFICE.

JAMES S. MOORE, OF GRAFTON, WEST VIRGINIA.

GLASS-WORKING MACHINE.

Application filed March 15, 1921, Serial No. 452,411.

This invention relates to glass working machines of the type used in the manufacture of glassware by blowing, such machines having intermittently movable tables for parison receiving and blowing molds. In practice the tables are usually driven by compressed air supplied to cylinders, the piston rods thereof being connected to oscillating arms associated with the tables to move the same so that the parison may be transferred from a station on one table to a blowing station on the other table.

The invention forming the subject matter of this application appertains more particularly to an air supply system, or arrangement of pipes, air control valves, and means moving the tables and locking them, which system may also include another control valve and accessories to actuate a "kick-out" for the parison receptacles.

An air supply system which accords with my invention has a main supply pipe that communicates directly with control valves for cylinders, the piston rods thereof oscillating arms to intermittently move the tables, air under pressure being supplied to the control valves, then to the cylinders to effect movement of the two tables at predetermined intervals.

My invention also includes locks for the tables and actuating means for the locks comprising pistons that are operated by air pressure supplied through branches of the air system connected to pipes which extend from the control valves to the cylinders whose piston rods actuate the table moving means.

The invention further consists in providing the table for the parison receptacles with a "kick out," the air supply therefore being connected with the control valves for the table moving and locking means.

My invention also includes in combination with an air line system for table moving and locking instrumentalities, means for synchronizing the movements of the tables, the locks thereof, and a "kick out" for parison receptacles, the elements being organized for automatic operation, as will be hereinafter set forth.

The invention further consists in the construction, arrangement and organization of parts, as will be hereinafter set forth and claimed.

In the accompanying drawings,—
Figure 1 illustrates a diagrammatic side

elevation of an air line system for glass working machines having tables or movable supports for the parison receptacles and for the blowing molds, certain parts being shown in section;

Figure 2 illustrates a horizontal longitudinal section of a cylinder or casing for a control valve;

Figure 3 illustrates a vertical longitudinal section of the cylinder or casing, the valve thereof being shown in full lines; and

Figure 4 illustrates a transverse section on the line 4—4 of Fig. 3, this view being projected from Fig. 2.

The invention forming the subject matter of this application is adapted for use in connection with glass working machines of that type manufactured under several Letters Patents of William J. Miller of Swissvale, Penn., for instance Patent Number 1,515,962, which are adapted to make jars, bottles and the like.

Referring to the drawings, 1 is a table or support for the parison receptacles, 2 the table or support for the blow-molds, said tables being intermittently rotated by piston rods 3 and 4 which are connected to oscillatory arms 5 and 6 attached to depending shafts of the tables, as is common, to insure intermittent rotation of the table. The piston rods are reciprocated at the proper intervals by air admitted into the cylinders 3' and 4' and the tables between the oscillations of the arms 5 and 6 are held or locked against rotation by vertically movable pins 7 and 8, which when elevated enter recesses formed in the under sides of the tables.

Air under compression for moving the tables and the locks is supplied through a main supply pipe 9 and its branches 10 and 11, such branches being connected to centrally positioned ports 12 of the cylinders or casing of 13 and 14 for control valves of similar construction. The cylinder 13 has ports 15 and 15' and the cylinder 14 has ports 16 and 16', said ports being located to one side of the transverse centers of the cylinders, and said cylinders are also provided at their ends with openings or ports 17, 17' and 18, 18', said ports preferably extending through the heads of the cylinders.

The cylinders or casings for the control valves (see Fig. 3) have ways 19 which communicate by openings 20 and 21 with the valve chamber adjacent to the ends thereof and the way 19 is also provided with a cen-

tral opening 22 located opposite the port 12. The casings or cylinders have threaded apertures for the reception of bolts 23 of a length to extend into the way 19 the bolts 5 when adjusted to suit the normal pressure in the main air line 9 determining the amount of air that will pass through the openings 20 and 21 in a given time.

The control cylinders have therein cylindrical sliding valves or spool valves 24 which have peripheral heads 25 and 25' positioned adjacent to the ends and a central peripheral portion 25" of less width than the heads, the length of the valve being less than the 10 distance between the heads of the cylinder.

The casings or cylinders 13 and 14 which are supplied with air under compression directly from the constant pressure supply pipe 9 are connected by pipes 26, 26' and 20 27, 27' with the cylinders 3' and 4', and these pipes are connected to pipes 28, 28' and 29, 29' with the cylinders 30 and 31 which have therein piston heads the piston rods thereof engaging levers 7' and 8' which carry beyond their fulcrums, pins 7 and 8 that engage with recesses or stops on the under surfaces of the tables. The table engaging pins and the levers are carried by suitably supported frames which also maintain 25 springs which tend to hold the pins raised and the pistons depressed.

The cylinders 13 and 14 at their ends have ports which are alternately closed by the reciprocation of the control valves 24, and 30 these ports 17, 17' and 18, and 18' communicate with pipes 32, 32' and 33, 33', the ends of said pipes having valves with springs for holding the same against their seats.

The valves 9', 10', 11' and 12' in practice 40 will be moved from their seats by suitable means as rods or pins operated either by air pressure or mechanically by suitable timing mechanism under air control, or by cams or the like that are actuated from the shafts 45 of the table supports.

When it is desired to associate the table actuating and locking means with a "kick-out" for the parison receptacles and to have the same operate synchronously or in proper time relation with the movement of the table 1, or with a transfer mechanism, I provide a cylinder 34 having therein a control valve of similar construction to the valves of cylinders 13 and 14. The end ports of 50 the cylinder 34 are connected by pipes 35 and 35' with pipes 32' and 33' and the ends of said pipes are provided with valve casings 10' and 11'. The port of the cylinder 34 which corresponds with the ports 15 and 55 16 of the valve casings 13 and 14 is connected by a pipe 36 which extends to the upper portion of a cylinder 37 which contains a "kick-out" piston for the parison. The pipe 36 has a by-pass or connection 38 that 60 extends to one end of a timing cylinder 39,

the piston therein having a rod for moving the valve 9' in a casing 40 off its seat. The port of cylinder 34 which corresponds with ports 15' and 16' of cylinders 13 and 14 is supplied with a pipe 41 that extends to the 70 lower end of the "kick out" cylinder 37; a branch 42 of pipe 41 which has a manually operated speed control cock or regulator 43 communicates with the timing cylinder 39. The cylinder 34 may be connected to the 75 main supply pipe 9 by a branch pipe 34', which corresponds with the pipes 10 and 11 of the casings 13 and 14.

The "kick out" cylinder has a valved port 44 which is adapted to be covered by the piston head when in lowered position.

The "kick out" rod of the piston head when forced upward extends through openings through the table 1, and engages with a part of the receptacle to raise the parison 85 of molten and plastic glass.

Several valves are held upon their seats by springs so as to be normally closed and the valves 10', 11' and 12' in practice will be moved from their seats mechanically by 90 pins which are actuated by cams on shafts which are actuated from the shafts or rotary supports for the tables.

By adjusting the bolts 23 the amount of air that enters the cylinders 13, 14 and 34 through the ports 20 and 21 may be regulated and thus the reciprocation of the spool valves 24 can be synchronized or timed as to the admittance of air under pressure to move the table and the table locks at the proper moment by the full pressure supplied between the heads or flanges and the center flange on the control valves.

The cylinder 34 is supplied with air under pressure by means of a branch pipe 34' from 105 pipe 9 which communicates with an inlet or opening 12" of the cylinder 34. This branch is similar to the branches 10 and 11 for the cylinders 13 and 14.

I claim:

1. In a glass working machine comprising in combination a rotatable table for parison receptacles, pneumatically actuated means for raising a part of a parison above the upper edge of a receptacle, a pneumatically operated table lock operative to hold the table against movement when a parison receptacle is positioned above the means for raising a part of the parison, pneumatically operated means for imparting movement to the table, independent pneumatically reciprocated control valves provided adjacent to their ends with heads and with a central portion of less width than said heads, cylinders for said valves, said cylinders having end ports which are alternately closed by end portions of the valve, outlet ports which alternately communicate with spaces between the central portion and heads of the valve, and a source of air pressure common 110 to the cylinders 115

120

125

130

to each of the cylinders in which the valves operate.

2. In a glass working machine having a table for blowmolds, an air supply which includes means actuated by fluid pressure for intermittently moving the table and other means for locking the table between its intermittent movements, a casing, a control valve in the casing, said valve comprising end heads and a central head carried within a casing of greater length than the distance between the end heads, said casing having a

longitudinal way provided with end ports and a central port, means between the end and central ports for reducing the area of a portion of the said longitudinal way, exit openings adapted to be alternately closed by the extreme ends of the control valve, and ports which are placed alternately in communication with pipes through which fluid pressure is supplied to actuate the table moving and the table locking means. 15 20

JAMES S. MOORE.
